INVENTOR.

William D. C. Lloyd

United States Patent Office.

WILLIAM D. C. LLOYD, OF LOUISVILLE, KENTUCKY.

Letters Patent No. 114,160, dated April 25, 1871.

IMPROVEMENT IN COOKING-STOVES.

The Schedule referred to in these Letters Patent and making part of the same.

I, WILLIAM D. C. LLOYD, of the city of Louisville, county of Jefferson and State of Kentucky, have invented a certain new and useful Improvement in Cooking-Stoves, of which the following is a specification.

The nature of my invention consists more especially in providing an air-chamber in the sunk part of the stove-hearth immediately under the fire.

This chamber is formed by a corrugated plate, with ribs on top to hold up the wood.

This plate is neatly fitted in the recess or sunk part of the hearth, and secured in such a manner as to be almost air-tight, leaving about two or more inches air-space between the plates.

The back end of this air-chamber forms a part of the side of the oven, and is perforated with a number of small holes, through which heated air is drawn into the oven through similar holes in the front end of the air-chamber, which holes are closed by a neatly-fitting cover, made circular, so as to form a small chamber in front of the holes, through which the air is drawn in by means of a small pipe connecting the chamber with an opening in the bottom of the hearth below, thereby preventing all ashes or dirt from entering the air-chamber.

The great advantages which I claim for my improvement are, that, by the use of the air-chamber immediately under the fire, it keeps the plates cool and prevents them from burning, and also prevents the oven-plate below from being highly heated, so as to burn the article cooking, and in order further to protect it the plate may be coated with a composition of alum and asbestos, by which, and with the addition of the heated air constantly rushing in through the chamber, the temperature of the oven becomes perfectly uniform throughout, and may be regulated to any degree of heat required, while all smoke or gas passes off through the holes connecting the oven with the flues of the stove, thereby avoiding all obnoxious vapors in the room where it is used, the openings admitting air into the chamber being closed when necessary by means of sliding covers in order to regulate the temperature in the oven, so that one side of the article cooking may not burn before the other is done

Having thus fully described the nature of my invention, a more complete understanding of which may be had by reference to the drawing—

Figure 1 is a view of the stove with a part of the side left out in order to show the interior of the oven and the situation of the air-chamber in the hearth.

Figure 2 is a view of the front of the stove, showing the hearth with the air-chamber in the recess, and also the covers by which the holes are closed, and connected with openings in the bottom and sides of the hearth, through which the air is supplied.

A is the stove.

B is the oven.

C is the hearth.

D is the air-chamber in the recess.

E is the corrugated plate by which it is formed.

F F F are the ribs which hold up the wood.

G G G are the air-holes in front of the chamber.

H are the covers by which they are closed.

I is the pipe connecting it with an opening in the bottom.

J J J are the air-holes in the bottom and sides.

K is the recess in the hearth.

L L L L are the holes through which the heated air passes into the oven.

P P are the discharge-holes connecting the oven with the flues, by means of which the oven is ventilated.

N is the front, showing the opening for the doors.

Q is the fire-place of the stove.

Having thus fully described the drawing,

What I claim as new, and desire to secure by Letters Patent, is—

The air-chamber D with its holes G G G and L L L, and corrugated plate E with ribs F F F to hold up the wood, in combination with the cover H, pipe I, air-holes J J J in recess K, and vent-holes P P in the oven, when arranged, constructed, and operating substantially as and for the purpose herein set forth.

WILLIAM D. C. LLOYD.
